UNITED STATES PATENT OFFICE.

NELSON H. FAIRWEATHER, OF EVERETT, MASSACHUSETTS, ASSIGNOR TO GILLETTE SAFETY-RAZOR COMPANY, OF BOSTON, MASSACHUSETTS, A CORPORATION OF DELAWARE.

PILE WIRE.

Application filed February 10, 1923. Serial No. 618,305.

My invention relates to pile wires such as are used in weaving cut-pile fabrics and have detachable blades, and is particularly applicable to pile wires which are of relatively small size and are thin in proportion to their height, its object being to improve upon the means heretofore employed for holding the detachable blades in place in the wires. The features in which my invention 10 resides are hereinafter described in connection with the accompanying drawing, in which—

Figure 1 is a side elevation of a portion of a pile wire embodying my invention in its 15 preferred form, showing the blade in place in the wire;

Figure 2 is a top plan view of the same portion of the wire, with the blade omitted; and

Figure 3 is a transverse section on the line 3—3 in Figure 1.

The construction illustrated in the drawing consists essentially of a pile wire 2 provided near its free end with a longitudinally-extending recess 3 adapted to receive a removable blade and having side walls which are thin enough to yield slightly under a moderate pressure and are so spaced that they are forced apart by the insertion of the 20 blade, with the result that the elasticity of the metal of which the wire is made causes the side walls of the recess to exert a frictional grip on the sides of the blade and thereby hold it in the recess. The form of the blade preferably employed, shown at 4, is a flat-sided blade of substantially triangular shape with a straight lower edge and upwardly-converging front and rear edges, of which the rear edge 5 is the cutting edge.

The recess 3 extends downward into the wire from its upper edge, and when the blade is in operative position therein its lower edge is seated on the bottom of the recess and its upper portion projects above the top 40 of the wire, as shown in Figure 1, with its rear edge slanting downward and rearward in the central plane of the wire.

The recess 3, in the form shown in the drawing, has a flat bottom with upwardly-curving front and rear ends, due to the formation of the recess by means of a small circular saw which is fed downward into the wire to the required depth and then traversed lengthwise thereof until a groove of

the desired length is obtained. The saw 55 employed is preferably slightly thicker than the blade, and after it has been withdrawn from the groove the side walls of the recess are pressed inward a few thousandths of an inch at about the longitudinal center of the 60 groove, as shown at 6 in Figure 2, thereby enabling them to exert the gripping action above described, which may be made permanent by suitably tempering the wire.

In order to prevent the blade from being 65 moved longitudinally in the recess during use I provide a stop preferably consisting of a transverse pin 7 inserted in the wire near the front end of the recess and slightly above its bottom, in position to be engaged 70 by the front edge of the blade. In case the blade has a slanting front edge, as shown, this stop 7 will evidently overhang the lower edge of the blade, with the result that any pressure exerted on the blade and tending 75 to force it forward in the wire will cause its rear end to hug the bottom of the recess and thus effectively prevent any possible tendency of the blade to tilt in the recess.

In addition to the simplicity of the construction above described and its freedom from any opening in which flights of yarn may catch it has the important advantage that blades differing in length can be used with equal facility, thereby avoiding the expense involved in accurately constructing the blades to standard dimensions. Other advantages reside in the complete absence of special locking devices or moving parts of any sort for holding the blade in place, 80 and in the facility with which the blade can be inserted and removed, which is accomplished by merely gripping the upper portion of the blade between the jaws of a suitable tool, such as a pair of pliers, and then 85 forcing it into or withdrawing it from the recess, as the case may be.

I claim:

1. A pile wire provided with a longitudinal recess terminating at both ends within the wire and open at the upper edge of the wire for the reception of a removable blade, said recess being bounded laterally by resilient walls which are integral with the wire and are so spaced as to exert a frictional retaining grip on the sides of the blade when inserted in the recess.

2. A pile wire provided with a longitudi-

nal recess terminating at both ends within the wire and open at the upper edge of the wire for the reception of a removable blade, said recess being longer than the blade and
5 being bounded laterally by resilient walls which are integral with the wire and are so spaced as to exert a frictional retaining grip on the sides of the blade when inserted in the recess, and a stop carried by the wire
10 in position to be engaged by the front edge of the blade.

3. A pile wire provided with a longitudinal recess terminating at both ends within the wire and open at the upper edge of the
15 wire for the reception of a removable blade,

said recess being bounded laterally by resilient walls which are integral with the wire and are so spaced as to exert a frictional retaining grip on the sides of the blade when inserted in the recess, in combination with a blade having upwardly converging front and rear edges and adapted to seat on the bottom of the recess, and a transversely-extending stop carried by the wire in position to be engaged by the front edge of the blade above the bottom of the recess. 20
